UNITED STATES PATENT OFFICE

153,240

DESIGN FOR A SPECTACLE FRONT

Raymond F. E. Stegeman, Greece, N. Y., assignor
to Bausch & Lomb Optical Company, Rochester,
N. Y., a corporation of New York

Application October 24, 1947, Serial No. 142,130

Term of patent 14 years

(Cl. D57—1)

To all whom it may concern:

Be it known that I, Raymond F. E. Stegeman, a citizen of the United States and a resident of the town of Greece, county of Monroe, and State of New York, have invented a new, original, and ornamental Design for a Spectacle Front, of which the following is a specification, reference being had to the accompanying drawing, forming a part thereof.

Fig. 1 is a top plan view of a spectacle front, embodying my new design.

Fig. 2 is a front elevational view of the same showing the essential features of my design in full lines.

I claim:

The ornamental design for a spectacle front, substantially as shown and described.

RAYMOND F. E. STEGEMAN.
